UNITED STATES PATENT OFFICE.

JOHN T. DUFF, OF ALLEGHENY, PENNSYLVANIA, ASSIGNOR OF ONE-THIRD
TO JOHN M. MONTGOMERY, OF SAME PLACE.

MACHINE FOR FLANGING CIRCULAR PLATES.

SPECIFICATION forming part of Letters Patent No. 274,115, dated March 20, 1883.

Application filed October 3, 1882. (No model.)

To all whom it may concern:

Be it known that I, JOHN T. DUFF, a citizen of the United States of America, residing at Allegheny, in the county of Allegheny and State of Pennsylvania, have invented certain new and useful Improvements in Machines for Flanging Circular Plates, of which the following is a specification, reference being had therein to the accompanying drawings.

10 My invention relates to an improvement in machines for flanging circular plates; and it consists in two adjustable horizontal rolls placed side by side, between the ends of which the edge of the circular plate to be flanged is inserted. The plate is attached to a vertically-revolving disk or head, over which its edge projects, which projecting edge is inserted between the ends of the rolls, and by them held while the disk with its support moves to the 15 extent of a quarter of a circle to the right or left, until its face is on a straight line with the ends of the rolls, when the flange is completed.

The accompanying drawings represent my invention.

20 Figure 1 represents a plan view of the machine; Fig. 2, a side view of the same. Fig. 3 represents the under side of the quadrant on which the guide and its support stand; Fig. 4, cross-section of the disk and its support.

25 On the frame *a* are two adjustable journal-beds, *b* *b'*, on which the shafts *e* *e'*, that carry the gear-wheels *d* *d'*, rolls *f* *f'*, driving-pulley *v*, and fly-wheel *w*, are journaled. The journal-beds *b* *b'* are adjustable by the screws *c* *c'*, so that the rolls can be made to approach each other more or less, as may be required to impinge on the plate to be flanged, be it of any thickness whatever. The rolls *f* *f'* at the forward ends of the shafts *e* *e'*, at the outside of 30 the frame, are operated by the pulley *v* at the end of one of the shafts and the gear-wheels *d* *d'*. Should the two wheels *d* *d'* be moved so far apart that their teeth no longer engage, the friction of the roll *f'* against the side of 35 the plate being flanged will be sufficient to cause the roll *f'* to revolve with the one *f*.

40 Under the forward ends of the rolls, at the center *i* of the semicircle formed by the base-plate *g*, is pivoted the arm which holds the frame *h* in place as it is moved back and forth on the base-plate. On the circular part of the

base-plate are suitable slide-bearings to secure a steady motion to the quadrant *h* when turning on it. The quadrant carrying the support *q* of the guide *n* is, by an arm, *h*, pivoted at *i*, 55 held and guided on the slide-bearings on the base-plate *g*. The pivot *i* is placed at the center of the circle formed by the circular base *g*, and may be entirely separate from the machine. 60

On the guide *n* is an adjustable journal-box, *s*, in which the vertically-rotating disk *m* is journaled, the box being movable toward or away from the faces of the rolls, by means of a screw, or in any other suitable manner. 65

At the under side of the quadrant *h* is a rack, that gears with the wheel *x* under the base-plate, which wheel is placed near the outer end of the arm of the base-plate, upon a shaft, and turned by a wheel or pulley, *z*, at 70 the end of that shaft. Thus the guide *n*, with its support *q*, is made to partially revolve on the stationary base-plate until it arrives at the end of the semicircle, on a straight line with the faces of the rolls, having passed over a 75 quarter of a circle.

The disk *m* stands on a radial line of the semicircular base-plate, its edge toward the rolls, and revolves upon its axis in the box *s*. The disk's surface is flat, and its diameter less 80 than that of the metal plate to be flanged, of which the edge protruding over the edge of the disk is to be bent at a right angle. The metallic plate is rigidly mounted on the disk by a suitable holder, and both revolve together. 85 If, after a proper adjustment of the rolls, so as to impinge upon the protruding edge of the metallic plate inserted between them, the pulleys *v* and *z* are set in motion, the quadrant *h* with its superincumbent mechanism begins to 90 move around on the base-plate *g*. The disk's face, with the metallic plate attached to it, remains during its motion around the center *i* on a radial line of the circle in which it moves, and causes thereby the edge of the metallic plate, 95 that is retained in its first position between the rolls, gradually to be bent, and when the disk's face arrives on a direct line with the front of the rolls, or at a right angle to its first position, the rectangular flange is completed. During the circular rotation of the quadrant the edge of the metallic plate is by the revolving-

rolls carried onward, so that the plate and disk are made to revolve in proportion to the rapidity of motion of the rolls.

From the foregoing it will be observed that in this machine many of the complicated devices in flanging-machines heretofore in use are done away with. The use of pivoted tables, springs, cams, and other devices that frequently encumber the machinery is avoided, and screws only applied to effect an adjustment suited to all thicknesses of the metallic plates. Free access is given to the workman to place and remove the hot plates without exposing himself to great heat, and the simplicity of the work to be performed is such that it can be carried on with great rapidity. The making of rectangular flanges on heavy circular plates has always proved a difficult task, which few, if any, have accomplished; but with the machine described the difficulty ceases, and no hammering is required to make the flanges what they ought to be—rectangular.

Having thus described my invention, I claim—

1. In a flanging-machine, the combination of

the rolls *f* and their operating mechanism, the guide *n*, the sliding journal-box *s*, carrying the adjustable head *m*, and the screw and its operating mechanism, substantially as shown.

2. In a flanging-machine, the combination of 30 a semicircular base-plate, a quadrant pivoted at the center of the circle formed by the base-plate, and a mechanism for moving the quadrant on the base, a guide secured to and moving with the quadrant, a revolving head journaled on the guide and made adjustable back and forth, and a pair of revolving rolls, substantially as specified.

3. The combination of a semicircular base-plate, a quadrant, and an operating mechanism for operating it, a suitable elevated guide carried by the quadrant, a revolving head journaled on the guide, and a pair of revolving rollers, substantially as set forth.

In testimony whereof I affix my signature in 45 presence of two witnesses.

JOHN T. DUFF.
